UNITED STATES PATENT OFFICE.

JAFEW S. VAN BUREN, OF ALBANY, NEW YORK, ASSIGNOR TO ABRAM COX STOVE COMPANY, OF PHILADELPHIA, PENNSYLVANIA, A CORPORATION OF PENNSYLVANIA.

DESIGN FOR A GAS-RANGE.

44,599.

Specification for Design. Patented Aug. 26, 1913.

Application filed June 14, 1913. Serial No. 773,769. Term of patent 14 years.

To all whom it may concern:

Be it known that I, JAFEW S. VAN BUREN, a citizen of the United States, residing in Albany, county of Albany, State of New York, have invented a certain new, original, and ornamental Design for a Gas-Range, of which the following is a specification, reference being had to the accompanying drawing forming part thereof, the figure in which is a front view showing my new design.

I claim:—

The ornamental design for a gas range as shown.

JAFEW S. VAN BUREN,

Witnesses:

CLYDE T. MOYER,
W.M. A. BARR.
